CIGARETTE AND METHOD FOR MAKING
SAME

Robert John, New York, N. Y.

No Drawing. Application August 10, 1931,
Serial No. 556,311

7 Claims. (Cl. 131—52)

The object of my invention is to decrease the irritant fumes usually found in cigarette smoke; to enhance the flavor of the tobacco through purely physical means without changing the constituents of the cigarette, to trap the fine particles of dust and tobacco which, when inhaled, become an annoying irritant, and to further trap tars and resins found in cigarette smoke which also act as irritants when inhaled, 10 and to avoid unpleasant after-taste.

As conventionally manufactured, the tobacco used in cigarettes has admixed therewith substances such as glycerine, flavoring materials, honey, molasses, and other forms of sugars; or 15 in some cases sugars are formed directly in the tobacco during its process of curing.

The addition of such materials to the tobacco before it is used to make cigarettes has supposedly been advisable for two reasons; (1) 20 being hygroscopic, such materials prevent the loss of moisture in the tobacco and pick up and store moisture when subjected to damp air; and (2) it has been believed that glycerine, honey and compounds of sugar when present 25 unchanged in the smoke, add to the smoothness of the smoke and in some measure offset irritants which have been formed due to the burning of the tobacco.

It is known, however, that cigarettes are subject to three distinct processes during the 30 consumption thereof, these being: (1) combustion, (2) destructive distillation, and (3) steam distillation.

It is also known that when glycerine and 35 sugars are burned or subjected to destructive distillation, as in the combustion stage of the cigarette fire-front, irritant aldehydes, such as acrolein, furfural, formaldehyde and acetaldehyde are formed. Also that glycerine and syrups 40 are capable of passing over unchanged when subjected to steam distillation such as occurs immediately back of the fire-front.

I have analyzed the constituents of cigarette smoke created under varying conditions and 45 have observed the following facts: If the cigarette be lighted and placed in a vertical position and permitted to burn naturally, merely by providing a stream of fresh air to support combustion without applying pressure, the smoke 50 produced contains more than ten times the percentage of aldehydes than is found in the smoke taken from the other end of the cigarette after normal puffing. I account for this by pointing out that the smoke mentioned in the first instance, called side stream smoke, is the result

of combustion and destructive distillation, while in the main stream smoke, such as is produced by puffing a cigarette, the aldehydes formed are minimized through the agency of steam distillation. However, my observations indicate that even in main stream smoke as above described, 60 in spite of the lessening of their quantity through steam distillation, there are still present definitely measurable quantities of irritating elements in the smoke which are highly objectionable. 65

In the present art of cigarette manufacture, it is customary to admix glycerine, syrups, flavoring matters, and the like with moisture contained in the tobacco before the cigarettes 70 are formed; thus the cigarettes are made of tobacco containing a practically uniform and homogeneous mixture of the added substances, which are capable of burning and being destructively distilled to form the objectionable irritants aforesaid. 75

My invention aims to reduce, if not substantially prevent, the formation of such irritants.

In carrying out my invention, I omit glycerine, 80 syrups, flavoring materials, and sugars from the tobacco during its process of manufacture completely. After the cigarette has been formed, I take a solution of the omitted constituents in such proportions and in such concentration that a measured quantity of the mixture may be applied to either or both ends of the finished cigarette, whereupon it will adhere to and be absorbed by the tobacco which it touches, without penetrating the cigarette more than, say, one-sixteenth of an inch. 85

The cigarette thus formed, if torn apart and analyzed, shows exactly the same percentages of each constituent as would the same kind of cigarette made by the practice of the existing art, the difference being that in the case of my improved cigarette, the body of the tobacco contains no added substances which are capable of burning into irritating aldehydes, these substances now being confined to a space of, say, 90 one-sixteenth of an inch from either end. 95

The material so applied to the end which goes in the smoker's mouth obviously is never burned but, through its hygroscopic nature, serves as a trap to absorb any dust or fine tobacco particles which the cigarette may contain, as well as to 100 absorb and hold certain of the tars which are formed.

As to the layer of material which has been applied to the end of the cigarette which is lighted, one might suppose that this would give 110

rise to temporary discharge of irritant vapors. In practice, however, I find that this is not the case, due to the unusual amount of moisture present as a result of the hygroscopic nature 5 of the material, which moisture sufficiently increases the factor of steam distillation to prevent the formation of aldehydes and irritants in the inhaled smoke, which would otherwise be present.

10 Naturally many hygroscopic materials may be utilized in carrying out my invention to practice. As a typical example, I recommend, assuming a cigarette to weigh 1 gram, that the solution applied to the ends thereof contain 15 1.5% glycerine, .5% honey, .5% maple sugar, 3% cane sugar, and .5% cocoa. A paste of the foregoing is made and 30 milligrams are applied to each end of the cigarette.

I may apply this solution to one or both ends, 20 but I prefer to apply it to both ends, inasmuch as it thereby more effectively seals the cigarette and protects the same.

By practicing the foregoing procedure, I find that the pleasing qualities of the tobacco are 25 accentuated and emphasized through the absence of added irritants in the smoke, while the added flavors are made more delightful as a result of the smoke passing through the layer imprisoned at the mouth end of the cigarette. 30 The moisture content of the tobacco is not interfered with and steam distillation proceeds as effectively as in the untreated cigarette and the unchanged vapors of the added constituents carried by the smoke give a new sensation of 35 smoothness to the smoker. Moreover, the actual taste of the added ingredients is somewhat enhanced, since they are concentrated at a point which is touched by the smoker's tongue. The combustibility of the cigarette has not been 40 disturbed.

I recognize, of course, that varying solutions may be used. I also recognize that if desired, only one ingredient, such as glycerine, may be omitted, leaving the other ingredients admixed 45 with the tobacco during its manufacture, and that the glycerine, which has been omitted, may, after the formation of the cigarette, be applied to either or both ends of the cigarette as desired.

What I claim is:

50 1. The herein described process of manufacturing cigarettes, the steps of which comprise the manufacture of the tobacco without the addition thereto of hygroscopic flavoring materials such as glycerine, sugars, honey or like 55 substances, forming a cigarette therefrom and impregnating after the formation of the cigarette, the tobacco of at least one end portion thereof with a hygroscopic flavoring material for increasing the flavor of the cigarette, where- 60 by the formation of undesirable irritants and fumes incident to the combustion of such materials is eliminated.

65 2. A cigarette of the class described having the tobacco of the body portion thereof substantially free from added flavoring materials such as glycerine, sugars, honey or the like, and having the tobacco immediately adjacent at least one

end thereof impregnated with a hygroscopic flavoring material to enhance the flavor of the cigarette and to reduce the formation of irritants and undesirable fumes during the consumption of the cigarette.

80 3. A cigarette of the class described having the tobacco of the body portion thereof substantially free from added flavoring materials such as glycerine, sugars honey or the like, and having the tobacco immediately adjacent at least one end thereof impregnated with a hygroscopic flavoring material in an amount substantially equivalent to the total amount normally distributed throughout the cigarette.

85 4. A cigarette of the class described having the tobacco of the body portion thereof substantially free from added flavoring materials such as glycerine, sugars, honey or the like, and having the tobacco immediately adjacent at least one end thereof impregnated with glycerine in an amount substantially equivalent to the total amount normally distributed throughout the cigarette.

90 5. A cigarette of the class described having the tobacco of the body portion thereof substantially devoid from added flavoring and hygroscopic material, such as glycerine, sugar, honey, or the like, which, when present, upon combustion thereof, would produce throat irritants, said cigarette having the tobacco of the 105 opposed tips only impregnated with a hygroscopic flavoring material whereby to seal the intermediate body portion of the cigarette and to prevent loss of moisture from the tobacco whereby the cigarette is maintained in substantially its same state of moisture as though the hygroscopic material were distributed throughout the entire cigarette.

100 6. A cigarette of the class described having the tobacco of the body portion thereof substantially 115 free from added hygroscopic flavoring materials, such as glycerine, honey, maple sugar, cane sugar, or cocoa, which, when present, have the effect of producing upon combustion of the cigarette, throat irritants, and having the tobacco immediately adjacent the opposed tip ends thereof impregnated to substantially one-sixteenth of an inch, with such hygroscopic flavoring material in an amount sufficient to maintain the tobacco intermediate the opposed tip portions in a substantially moist condition.

110 7. A cigarette of the class described having the tobacco of the body portion thereof substantially free from added hygroscopic flavoring materials, such as glycerine, honey, maple 120 sugar, cane sugar, or cocoa, which, when present, have the effect of producing upon combustion of the cigarette, throat irritants, and having the tobacco immediately adjacent the opposed tip ends thereof impregnated to substantially one-sixteenth of an inch, with such hygroscopic flavoring material in an amount substantially equivalent to the total amount of such materials normally distributed throughout the cigarette.
